BRASSIÈRE

Sam Gerstein, Brooklyn, and Irving Gerstein,
New York, N. Y.

Application September 10, 1951, Serial No. 16,599

Term of patent 14 years

(Cl. D20—4)

To all whom it may concern:

Be it known that we, Sam Gerstein and Irving Gerstein, both citizens of the United States of America, and residing respectively at Brooklyn, in the county of Kings and State of New York, and at New York city, in the county and State of New York, have invented a new, original, and ornamental Design for a Brassière, of which the following is a specification; reference being had to the accompanying drawing, forming a part thereof.

Fig. 1 is a front elevational view of a brassière, showing our new design.

Fig. 2 is a top plan view thereof.

Fig. 3 is a side elevational view thereof.

We claim:

The ornamental design for a brassière, substantially as shown.

SAM GERSTEIN.
IRVING GERSTEIN.
